United States Patent Office

Des. 233,336
Patented Oct. 22, 1974

233,336

LABEL FOR BATTERY

Harry M. Channing, Wyomissing, and Bernard J. Elzer,
West Reading, Pa., assignors to General Battery Cor-
poration, New York, N.Y.

Filed July 19, 1972, Ser. No. 273,198

Term of patent 14 years

Int. Cl. D20—03

U.S. Cl. D19—13

Fig. 1

Fig. 2

FIG. 1 is a perspective view of a label for battery em-
bodying our design; and

FIG. 2 is a rear view on a reduced scale of the label
for battery shown in FIG. 1.

We claim:

The ornamental design for a label for battery, as
shown.
